[57] **CLAIM**

The ornamental design for an installation tool for lap siding, as shown and described.

DESCRIPTION

FIG. 1 is a left side elevational view of an installation tool for lap siding, showing the preferred embodiment of the new design, the right side elevation being substantially a mirror image thereof;

FIG. 2 is a top plan view of the installation tool for lap siding of FIG. 1;

FIG. 3 is a bottom plan view of the installation tool for lap siding of FIG. 1;

FIG. 4 is a rear elevational view of the installation tool for lap siding of FIG. 1; and,

FIG. 5 is a front elevational of the installation tool for lap siding of FIG. 1.
